UNITED STATES PATENT OFFICE.

PERCY H. THOMAS, OF EAST ORANGE, NEW JERSEY, ASSIGNOR TO COOPER HEWITT ELECTRIC COMPANY, OF NEW YORK, N. Y., A CORPORATION OF NEW YORK.

MEANS FOR PRODUCING A VACUUM.

981,141.

Specification of Letters Patent. Patented Jan. 10, 1911.

Application filed January 23, 1904. Serial No. 190,283.

To all whom it may concern:

Be it known that I, PERCY H. THOMAS, a citizen of the United States, and resident of East Orange, county of Essex, State of New Jersey, have invented certain new and useful Improvements in Means for Producing a Vacuum, of which the following is a specification.

The present invention relates to means for producing a vacuum, and it is particularly applicable to such apparatus as is adapted, when completed, to contain a certain kind of fluid, such as mercury. According to this conception of the invention, the vessel forming the body of the apparatus should contain a volatilizable liquid capable of condensation and consequent restoration to liquid form.

A broader conception of the invention would contemplate the invention merely as a means for securing a vacuum for whatever purpose, and would not necessarily involve the use of the apparatus for a purpose to the accomplishment of which the presence of a condensed liquid would contribute. As an example, however, of a particular use to which the present invention adapts itself, I may mention the well-known mercury vapor electric apparatus, and for convenience the present specification will describe and the drawings will illustrate an apparatus of this class.

The principle of the invention resides in utilizing the vapor of a volatilizable liquid for carrying off the gases which it is desired to exclude from the containing vessel. To this end the vapor, which may be mercury vapor, is caused to be expelled by any suitable means from the vessel, carrying with it all deleterious gases. When this process has been continued long enough to purify the chamber of the vessel from all gases which it is desired to remove, the exit chamber is sealed off while the process of expulsion is going on, thus preventing any return of noxious gases into the chamber. In order to secure the best results, the sealing off should not take place until the time has arrived when the gases or vapors issuing from the exit chamber consist wholly of the vapor selected as the carrier for the noxious gases or of such other gases as may be utilized for the purpose of cleansing or evacuating the chamber.

My invention will be understood by ref-

erence to the accompanying drawing which is an elevation and part section of an apparatus adapted to carrying out my invention.

In the drawing, 1 is the container of a mercury vapor apparatus such as is adapted for use as a circuit-breaker for controlling electric circuits. The said container is supplied with electrodes, 2 and 3, one of which is the positive and the other the negative electrode of the apparatus. These electrodes may be of mercury or one of the said electrodes may be of mercury or other suitable conducting fluid and the other may be of a solid material, such as iron. Lead-wires, 4 and 5, are connected, respectively, with the electrodes 2 and 3. When the device is to be used as a circuit-breaker, the mercury may be caused to form a normal conducting path between the electrodes, as illustrated at 6. This, however, is a detail which may be varied according to circumstances, and it should be understood that this particular form of vapor apparatus is selected merely for the purposes of illustration. The same mode of manufacture may be employed whether the apparatus is to be used as a circuit-breaker, a lamp, a current rectifier, or for any other purpose.

I may place above the mercury in the container 1 a thin sheet or film, 7, of water for a purpose to be explained hereinafter. This film of water may, however, be omitted, if preferred.

The apparatus as shown is provided with an exit tube, 8, through which vapors or gases may be expelled before the sealing of the apparatus takes place. I generally surround the apparatus, during the process of manufacture, with a heat retaining shield, 9, the function of which may be readily understood. Below the apparatus I place one or more flames or torches 10, 10, for volatilizing the liquid in the container 1, or a portion thereof, and causing the removal of all injurious gases or vapors.

When the operation of creating a vacuum within the chamber is ready to begin, the jets 10, 10, are ignited and heat is applied to the container, causing, first, a vaporization of the film of water 7 and the expulsion of its vapor through the exit tube 8. By these means some of the injurious gases are removed. A portion of the mercury is then volatilized by the continued application

of heat, the gases originally contained within the apparatus disseminating themselves through the vapor thus produced and when the mixed gases and vapors pass out 5 through the exit tube 8, all of the injurious gases in the container are finally carried off. As already stated this process is continued until the gases passing through the exit tube 8 are practically pure mercury vapor. 10 The tube is then sealed off at 11, while the expulsion of the vapors is still in progress, whereupon the heat may be discontinued and the mercury may condense and flow back into the electrodes. In this way a 15 high degree of vacuum can be obtained without the use of an external pump which is itself capable of exhausting the chamber to the required degree.

The same process might be utilized for 20 producing a vacuum for any purpose as already explained.

In employing the term "volatilizable fluid" in the present specification and claims, it is intended to include substances 25 which may be acted upon by chemical or any other suitable means for producing the necessary gas or vapor for clearing the chamber.

The narrow throat 11 serves a critical 30 function in connection with the present invention, to wit, that it reduces the cross-section of the passage through which the vapor of mercury or other vapor utilized to expel the deleterious gases inclosed within the 35 chamber pass. By virtue of the narrowing of the cross-section as described, the velocity of the gas or vapor utilized for this purpose is greatly increased until it exceeds the velocity of the diffusion of any of the deleterious gases beyond the narrow throat.

When the exhaustion is complete or carried to a satisfactory limit, the apparatus may be sealed off at any point on the outside of throat 11.

It is well known that certain chemical processes which can be excited by suitable means produce large volumes of gases or vapors. Gases or vapors formed by such a chemical process may be utilized in place of the vapor produced from the mercury within the chamber by heat to secure exhaustion and when the process is sufficiently complete the chemical production of gases may be discontinued by the suppression of the exciting means.

In companion applications namely, Serial Number 265,503, filed June 16th, 1905, Serial Number 190,284, filed January 23rd, 1904 and in applicant's Patents 806,853 issued December 12th, 1905, and 845,670 issued February 26th, 1907 are found claims on subject matter related to that of the claims of the present case.

I claim as my invention:—

1. In an apparatus for exhausting a hermetically sealed chamber through the action of vaporization and expulsion of a volatilizable liquid, auxiliary expelling means said means consisting of an additional more easily volatilizable liquid introduced in the chamber prior to exhaustion.

2. A method of exhausting a hermetically sealed vessel containing a volatilizable liquid which consists in adding a second more volatilizable liquid, supplying heat to the second liquid for the purpose of washing out deleterious gases and expelling the vapors of the second liquid by vaporizing a portion of the first liquid and sealing the container during the expulsion of the vapors from the first named liquid.

Signed at New York, in the county of New York, and State of New York, this 11th day of January, A. D. 1904.

PERCY H. THOMAS.
